DESIGN FOR A GLOVE

John E. Fuchs, New York, N. Y.

Application September 20, 1937, Serial No. 71,689

Term of patent 3½ years

To all whom it may concern:

Be it known that I, John E. Fuchs, a citizen of the United States of America, residing in the city of New York, State of New York, have invented a new, original, and ornamental Design for a Glove, of which the following is a specification, reference being had to the accompanying drawing, forming part thereof, wherein,

Fig. 1 is a rear view of a glove showing my design; and

Fig. 2 is a front view of the glove shown in Fig. 1.

I claim:

The ornamental design for a glove substantially as shown.

JOHN E. FUCHS.
